UNITED STATES PATENT OFFICE

EDWARD A. DOWNEY, OF DEL RAY, VIRGINIA, ASSIGNOR, BY DIRECT AND MESNE ASSIGNMENTS, TO JOHN A. MASSIE AS TRUSTEE, OF WASHINGTON, DISTRICT OF COLUMBIA

CONNECTER FOR VENTILATING RACKS OR TRAYS

Application filed March 30, 1927. Serial No. 179,644.

This invention relates to an attachment for railway cars, particularly to an auxiliary floor covering attachment for freight cars handling perishable produce, which is 5 adapted to provide ventilation below the produce, and yet more particularly to a hinged connecter for joining the several panels of the slatted and battened racks used to cover such floors.

10 The hinge device to be disclosed in the present application is related to and constitutes an improvement upon the hinge device described and claimed in my Patent No. 1,588,948, granted June 15, 1926, and has in 15 common with that invention as some of its several objects: the provision of a connecter which will permit the slatted panels or frames with which it is associated to be extended in the same plane, folded face to face, 20 or folded back to back; the provision of such a connecter which is simple in its structure, having few parts, so as to be inexpensive in its manufacture and application, smooth and reliable in its action, and durable in service; 25 and which will constitute a general advance in the art.

Among the objects more particularly appurtenant to the present invention alone may be mentioned: the provision of a hinged connecting device having the above mentioned desirable characteristics, which has its pivoted ends disposed beneath the slats of the racks upon which it is used so that such joints will not be exposed to dirt, dust or corroding or 35 gumming substances which would interfere with their action; and the provision of such a hinged connecter which will stand clear of the ends of the sections when the same are folded up so as to lessen its liability to be 40 damaged by trucks and other objects moving within the car.

Other objects will appear as the description of one form of improved connecting device proceeds. While the one preferred embodiment of the invention is being illustrated and described in detail, it is to be understood, however, that various changes and modifications are contemplated and may be made in the device within the scope of what 45 is claimed, without departing from the spirit

of the invention or sacrificing any of the advantages thereof.

In the drawings forming a part of this application:

Figure 1 is a diagrammatic plan view of 55 one section of a ventilating rack employing the present improved hinge device;

Figure 2 is a longitudinal sectional view through a portion of the rack showing the application of the connecting device, the section being taken on the line 2-2 of Fig. 1;

Figure 3 is a section generally similar to Fig. 2, but showing in full lines the hinged sections of the panel folded back to back and in dotted lines showing one of the panels folded face to face with the other panel; and

Figure 4 is a detail perspective view of the connecting device.

Referring particularly to the drawings, Fig. 1 illustrates one section of panels, there being four sections like the one shown attached to each car. Each section comprises intermediate panels 11 and 12 which are hingedly connected to the side of the car by hinges 13 in such manner that the panels may 75 be moved to a vertical position along the sides of the car.

To the outer end of each of the panels 11 and 12 are hinged panels 14 and 15 respectively. The panels 14 and 15 consist of longitudinal battens or stringers 16 and cross slats 17 secured to the top edges of the battens. The panels 11 and 12 likewise consist of battens 16 and cross slats 17, but the battens of the panels 11 and 12 are staggered 85 with relation to the battens of the panels 14 and 15 respectively.

It is desirable at times, in order to clean the main floor of the car and for other purposes, to fold the end panels 14 and 15 back 90 upon the intermediate panels 11 and 12 in face to face relation, the tops of the slats being regarded as the face of the panels, and at times for similar reasons it is desirable to fold the panels back to back. To permit the panels to be extended in the same plane upon the floor, folded face to face, or folded back to back when necessary, the improved connecting devices, generally designated by the numeral 18, are provided. Each connecting 100

device 18 comprises pivot members 20 and 21 adapted to be attached by their strap portions 20^a and 21^a to the under surface of the end slat of the adjacent hinged panels by bolts or rivets 24 passing through the slat and the strap. The bolts or rivets 24 are countersunk below the face of the slat in order to avoid injury to uncrated produce and the like placed thereupon. The pivot or hinge members 20 and 21 are preferably made of flat stock. One of the hinge members 20 is turned at its end adjacent the end of the panel to form an eye 20^b, while the other hinge member 21 is turned at its end adjacent the end of the other panel to provide the slotted opening or loop 21^b. When the panels are in alignment as shown in Fig. 2, both the eye and the loop extend from the same side of the straps, that is, they extend away from the slats 17. A connecting member or link 27 which in its specific form is made as a closed rectangular loop or ring has pivot portions 27^a which operate within the eye 25 and the loop 26 respectively. The connecting member has an intermediate portion 27^b which is offset to one side of the end portions and as shown in Figs. 2 and 4 is suspended so as to hang below its pivoted end portions. The width of the opening of the rectangular connecting member is substantially the same as the width of the walls of the pivot members 20 and 21 adjacent the eye and loop respectively, so that lateral movement of one panel with respect to the other is avoided.

The straps 20^a and 21^a of the pivot members 20 and 21 respectively are preferably secured to the under co-planar surfaces of the slats 17 so that the entire connecting device is located between the upper and lower surfaces of the panels. With this disposition of the device, no part of the same projects above the panel to injure goods stored thereon. It will also be seen by reference to Fig. 3 that the connected panels may be folded in either position as heretofore described, either face to face or back to back and when folded, no part of the connecting device likely to be damaged by a blow extends beyond the folded ends of the panels. The joints or pivot portions in all positions are disposed well beneath the end slats 17 where they will neither be damaged by blows nor be corroded or gummed by falling substances.

Having thus described the invention, what is claimed as new and desired to be secured by Letters Patent is:

1. A hinge device for connecting the adjacent ends of two frames or panels in such manner that the panels may be disposed in the same plane, folded face to face, or folded back to back, comprising a pivot member secured to one of the panels provided with a slot disposed adjacent but short of the end of the panel, a second pivot member secured

to the other of the panels provided with an eye disposed adjacent but short of the end of the panel, and a connecting member having one end portion slidably and pivotally connected to the first pivot member, its other end portion pivotally connected to the second pivot member and its intermediate portion offset with respect to its pivoted end portions to embrace the overhanging ends of the panels when the same are folded face to face.

2. The combination set forth in claim 1 but in which the longer axis of the slot in the first pivot member is arranged transversely of the surface of the panel with which it is associated.

3. The combination set forth in claim 1 but in which the connecting member is formed as a complete link or loop of substantially rectangular shape having a width of opening just sufficient to embrace the walls of said pivot members about the ends of said slot and eye respectively, whereby side play of the panels is resisted.

4. The combination set forth in claim 1 but in which the longer axis of the slot in the first pivot member is arranged transversely of the surface of the panel with which it is associated, and in which the connecting member is formed as a complete link or loop of substantially rectangular shape having a width of opening just sufficient to embrace the walls of said pivot members about the ends of said slot and eye respectively, whereby side play of the panels is resisted.

5. The combination with two panels arranged end to end and having substantially co-planar surfaces intermediate their upper and lower faces of a hinge device for connecting said panels in such manner that they may be disposed in the same plane folded face to face or folded back to back, said device including a pivot member having a slot disposed substantially transversely to said co-planar surfaces adjacent to but short of the end of one of said panels and having a strap portion extending along and secured against one of said surfaces, a second pivot member having an eye disposed adjacent but short of the end of the other panel and a portion extending along and secured against the other of said surfaces, and a connecting member extending through both the loop and eye of said pivot members respectively and positively connecting the same, no portion of the loop, eye or connecting member extending beyond the faces of the panels when arranged end to end and no portion of the pivoted joints between the pivot members and the connecting device extending beyond the ends of the panels in either the extended or folded positions.

6. A hinge device for connecting the adjacent ends of two frames or panels in such manner that the panels may be disposed in the same plane, folded face to face, or folded

back to back, comprising a connecting member having pivoting end portions and an intermediate portion offset to one side of the end portions, means disposed adjacent but short of the end of one of said panels for pivotally and slidably securing one end portion of said connecting member to said panel, and means disposed adjacent but short of the end of the other of said panels for pivotally securing the other end portion of said connecting member to said other panel.

7. A hinge comprising in combination, a pair of pivot members, one of which is provided with an eye and the other of which is provided with an elongated slot, the slot and eye projecting in the same direction when the hinge is open, and a connecting member, one end of which is pivoted in said eye and the other end of which is pivoted and slidable in said slot.

8. A hinge as set forth in claim 7, but in which said connecting member assumes a position substantially normal to the length of said slot when the hinge is open.

9. A hinge as set forth in claim 7 but in which said connecting member includes an intermediate portion which assumes a position substantially normal to the length of said slot when the hinge is open, and pivoted end portions offset from the intermediate portion on that side toward the eye and slot.

In testimony whereof I hereunto affix my signature.

EDWARD A. DOWNEY.
